UNITED STATES PATENT OFFICE.

CHRIS NOHR, OF PASADENA, AND PETER NOHR, OF LOS ANGELES, CALIFORNIA.

MACHINE FOR ROLLING SOLES.

Application filed October 24, 1927. Serial No. 228,238.

This invention relates to a machine for rolling and pressing soles applied to foot wear. Shoe soles are now cemented onto the shoe upper in many instances instead of 5 nailing or pegging, and when the sole is so applied it is desirable that the sole be firmly pressed and rolled out so that the cement will be of equal thickness therebeneath, forming a good strong bond between the 10 shoe sole and the shoe upper.

An object of the invention is to provide a machine for rolling and pressing shoe soles, which is easily and quickly operated, and which will exert the desired amount of 15 pressure on the shoe sole to accomplish the purposes above mentioned.

Another object of the invention is to provide a machine which is so constructed that the work can be easily and quickly applied 20 to the machine or removed therefrom.

A further object of the invention is to provide a machine which is of cheap, simple and durable construction, and which will effectively press and roll soles applied to foot 25 wear.

Another object of the invention is to provide a machine having a roller adapted to be passed over the bottom of a shoe sole to press it, and which is so constructed that the roller 30 will exert an equal pressure at different points over the shoe sole regardless of the curvature of the sole.

With the foregoing and other objects in view which will be made manifest in the following detailed description and specifically 35 pointed out in the appended claims, reference is had to the accompanying drawings for an illustrative embodiment of the invention, wherein:

40 Figure 1 is a view in side elevation of the improved machine, parts being broken away and shown in section.

Fig. 2 is a top plan view of the machine, 45 parts being broken away and shown in section.

Fig. 3 is a vertical section taken substantially upon the line 3—3 upon Figure 1.

Referring to the accompanying drawings 50 wherein similar reference characters designate similar parts throughout, the improved machine consists of a frame having a base

which may be made up of two angle irons 10 and 11 connected by cross bars 12, 13 and 14. Adjacent one end of the base there are secured two stationary uprights 15 and 16. 55 On the opposite end of the base a pair of uprights 17 and 18 extend upwardly and have secured thereto channels 19 and 20. If desired, the uprights 17 and 18 may be formed by merely bending the ends of these channels downwardly. The two channels 19 and 20 have their flanges or open sides extending toward each other and form tracks on the frame. Their rear ends are connected by a cross bar 21 which has a latch bar 22 secured thereto adapted to be engaged by 60 spring latches 23. The lower ends of the uprights 17 and 18 are pivoted as indicated at 24 so that the forward uprights and the channels may be swung forwardly or they 65 may be locked in the position shown in Figure 1 by the spring latches 23. A carriage 70 is provided which is in the form of a U-shaped yoke having parallel arms 25 and 26 which are somewhat crooked as shown in 75 Figure 1, and which have their upper ends connected by a cross bar 27. The arms 25 and 26 carry pintles 28 intermediate their ends, on which rollers 29 are rotatably 80 mounted. These rollers fit and roll within the grooves provided by the opposed channels 19 and 20. A roller yoke having parallel arms 30 and 31 connected by a cross bar 32, is carried by the carriage and the forward 85 ends of the parallel arms 30 and 31 are pivotally connected to the arms 25 and 26 as indicated at 33. On the cross bar 32 there is pivoted an upstanding bolt 34 which extends upwardly through a sleeve 35 and through the cross bar 27 having a wing nut 90 38 threaded onto its upper end. A coil spring 39 is disposed about the bolt and is compressed between the cross bar 32 and the sleeve 35. A cross bar 40 connects the arms 25 and 26, and has secured thereto a 95 rack 41 which rests within a notch formed in the center of a cross bar 42 connecting the two uprights 17 and 18. A short distance above the cross bar 42 there is a shaft 43 adapted to be rotated by means of a 100 crank 44 in bearings provided on the uprights. This shaft has a gear 45 keyed

thereto which meshes with the rack 41. The two cross bars 13 and 14 serve to support a last 46, which last constitutes a work-holder and is preferably replaceable or at least has a replaceable head so that it may accommodate work of various sizes. A brace member 47 is pivoted to one of the angle irons forming the base, and when the frame is in its forwardly extending position, this brace is adapted to enter a notch 48 in the upright 17 so as to support the frame in its elevated or forwardly swung position. A roller R is rotatably mounted on an axle 49 which connects the two arms 30 and 31 of the roller yoke.

The operation of the improved machine is as follows:

The work, which is a shoe upper, is mounted on the last 46 and has the sole applied thereto by means of cement. The frame is then swung downwardly into the position shown in Figure 1 and locked in this position by means of the latches 23. By rotating the crank 44 the rack 41 can be moved back and forth by means of the gear 45, causing the carriage to move back and forth with its rollers 29 rolling within the channels 19 and 20. As clearly shown upon Figure 1, the channels 19 and 21 are curved so that they are substantially parallel to the top surface of the last 46. The bolt 34 limits the downward movement of the roller yoke against the action of the coil spring 39, and by virtue of the fact that the track provided by the channels is curved, the roller R will be caused to move through a curved path parallel to the top of the last. The spring 39 urges the roller yoke and roller toward the last and causes the roller to exert a continual pressure on the shoe sole, which pressure will be substantially even all over the sole by virtue of the fact that the carriage moves on a track parallel to the last. By reciprocating the rack 41 back and forth several times, the roller R will be caused to press out the shoe sole and to squeeze out surplus cement. It also presses the shoe sole against the shoe upper so that a firm, strong, adhesive bond will be established therebetween by the cement. As soon as the roller R has been moved back and forth over the shoe sole, the desired number of times so that the sole will be firmly fastened by the cement, the latches 23 can be caused to disengage the latching bar 22 and the frame can be swung forwardly about its pivot 24. It can be held in this position by causing the brace 47 to enter the notch 48 while new work is being substituted for that already on the machine. The pressure exerted by the roller R against the shoe sole can be varied by tightening or loosening the wing nut 38 so as to raise or lower the position of the roller on the carriage.

From the above described construction it will be appreciated that a novel machine is provided which will efficiently, effectively and quickly cause a shoe sole to be firmly adhered to a shoe upper.

70

Various changes in the details of construction may be made without departing from the spirit or scope of the invention as defined by the appended claims.

75

We claim:

1. A device of the class described comprising a frame, a last on the frame, a carriage, said frame providing a track upon which the carriage is movable, and a roller carried by the carriage adapted to be moved over the last to press work thereagainst, said track having portions curved similarly to the top of the last.

2. A device of the class described comprising a last, a frame providing a track, portions of which are curved to correspond to the top of the last, a carriage movable upon the track, a yoke pivoted upon the carriage, a roller mounted for rotation upon the yoke, means urging the roller toward the last, and means for moving the carriage.

3. A device of the class described comprising a last, a frame providing a track, portions of which are parallel to the top of the last, a carriage movable upon the track, a yoke pivoted upon the carriage, a roller mounted for rotation upon the yoke, a bolt pivoted to the yoke and slidably extending through the carriage, a nut on the bolt, and a spring about the bolt between the yoke and carriage urging the yoke and roller toward the last.

4. A device of the class described comprising a last, a frame providing a track, portions of which are curved to correspond to the top of the last, a carriage movable upon the track, a yoke pivoted upon the carriage, a roller mounted for rotation upon the yoke, means urging the roller toward the last, a rack secured to the carriage and slideable on the frame, a gear meshing with the rack, and means for rotating said gear.

5. A device of the class described comprising a last, a frame having a pair of opposed channels providing a track having portions curved to correspond to the top of the last, a carriage having rollers disposed in said channels, a yoke pivoted upon the carriage, a roller mounted for rotation in the yoke adapted to engage work pressed on the last, spring means urging the yoke and roller toward the last, and means for moving the carriage over the track.

6. A device of the class described comprising a last, a frame having a pair of opposed channels providing a track having portions parallel to the top of the last, a carriage having rollers disposed in said channels, a yoke pivoted upon the carriage, a roller mounted for rotation in the yoke

125

130

adapted to engage work positioned on the last, spring means urging the yoke and roller toward the last, means for moving the carriage over the track, the portion of the frame extending over the last being pivoted so that it may be swung out of the way on applying and removing work, and latch means for locking the frame in its normal position.

In testimony whereof we have signed our names to this specification.

CHRIS NOHR.
PETER NOHR.
